[57] **CLAIM**

The ornamental design for a ground engaging element, as shown.

DESCRIPTION

FIG. 1 is a top perspective view of a ground engaging element, showing my new design;

FIG. 2 is a bottom perspective view thereof;

FIG. 3 is an enlarged top plan view thereof;

FIG. 4 is an enlarged front elevational view thereof;

FIG. 5 is an enlarged bottom plan view thereof;

FIG. 6 is an enlarged rear elevational view thereof;

FIG. 7 is an enlarged right side elevational view thereof; and,

FIG. 8 is an enlarged left side elevational view thereof.
